UNITED STATES PATENT OFFICE.

WERNER KOLBE, OF ESSEN, GERMANY, ASSIGNEE TO FRIED. KRUPP AKTIENGESELLSCHAFT, OF ESSEN-ON-THE-RUHR, GERMANY.

SETTING DEVICE FOR THE DISPLAY AND TYPE WHEELS OF CASH REGISTERS.

Application filed August 19, 1922. Serial No. 583,029.

To all whom it may concern:

Be it known that I, WERNER KOLBE, residing at Essen, Germany, a citizen of the German Republic, have invented a certain new and useful Improvement in Setting Devices for the Display and Type Wheels of Cash Registers, of which the following is a specification.

This invention relates to devices for setting the display and type wheels of cash registers and it has, more particularly, reference to devices of the kind comprising members oscillating to and fro for driving the setting discs by which the display and type wheels are, in a well-known manner, moved directly from the old to the new position without having to pass first through the zero-position.

The invention essentially consists in that a carrier for a planet-pinion which is in positive connection with the display and type wheels as well as with the setting disc, is moved into its zero-position, determined by a fixed stop, during the setting oscillation of the setting disc driving member. The display and type wheels are thereby rotated in accordance with the difference between the numeral value set in the previous operation of the cash register and the value to be newly set, the said rotation being either effected, in one sense, by rotating the setting disc while the carrier of the planet-pinion is stationary, or, in the other sense, by rocking the planet-pinion carrier while the setting disc is stationary. In the return oscillation of the setting disc the planet-pinion carrier will then come into a position which corresponds to the newly set numeral value.

An embodiment of the subject-matter of the invention is diagrammatically illustrated, by way of example, in connection with a key cash register in the accompanying drawing.

Fig. 1 is a partial side elevation of the cash register in inoperative position, after the value of the third key from below has been previously registered;

Fig. 2 is an elevation corresponding to Fig. 1, illustrating the position of the parts after the sixth key has been depressed and the setting oscillation caused thereby terminated;

Fig. 3 is an elevation similar to Fig. 2 after the return oscillation, and

Fig. 4 is a sectional view taken on the plane indicated by the line 4—4 in Fig. 1.

The setting discs A are mounted for free rotation on a shaft B with which the discs C, which serve to drive the setting discs, are rigidly connected. Each time the cash register is operated, the shaft B will have imparted to it a rocking motion in a well-known manner, by means of a crank mechanism not shown in the drawing, namely a setting oscillation in clockwise direction and a return oscillation. Each driving disc C possesses an offset c^1 adapted to be engaged with the offset toe of a setting bolt D which is pivotally connected to the setting disc A, further a cam pin c^2 for operation with a planet-pinion carrier E and another cam pin c^3 for returning the setting disc A into its zero-position. Mounted for oscillation by a pin a^1 on each setting disc A is a bell crank lever F engaging the setting bolt D. The setting bolts are tapered at their free ends and adapted to engage notches g^1 of a locking plate G. The bolts D are held in this position by the rim c^4 of the driving disc C. The setting discs A are further provided each with a recess a^2 (Fig. 2) for engagement by the pin c^3 of the driving disc C and with a toothed rim a^3 which is engaged by a planet-pinion H mounted on the carrier E and by a pinion J which is mounted at the casing and which is suitably coupled with the adding wheels during the setting operation. The carrier E, moreover, carries an intermediate pinion K which is in mesh with a planet-pinion H' and with the toothed rim b^1 of a double segment L. The planet-pinion H' is equal to the planet-pinion H and is fixed on the same shaft h^2 as the latter. The carrier E is provided at one side with a recess e^1 (Figs. 1 and 3) for receiving the cam pin c^2 and at the opposite side with a recess e^2 (Figs. 1 and 3) for a stop rod M which is fastened to the casing and which serves to limit the rocking movement of all of the planet-pinion carriers E. The arrangement of the rod M and the recesses e^1 , e^2 of the planet-pinion carrier E is made so as to cause the pin c^2 of the driving disc C to engage the recess e^1 , and to cause the recess e^2 to engage the rod M when, in the setting operation, the disc C has been swung into its uppermost position (Fig. 2). The double segment L possesses another toothed

105

rim ℓ^2 which is engaged by a toothed wheel N which serves to adjust the display and type wheels, not shown in the drawing, and which is adapted to be locked in its different 5 positions by a locking bar O adapted to be thrown into engagement with the wheel N.

The operation of the described device is as follows:

After preparing a registration by depressing 10 a key, an operation of the cash register will cause a to and fro oscillation of the driving disc C, the locking bar O releasing the toothed wheel N prior to the setting oscillation and locking it again prior to the 15 return oscillation. In the setting oscillation, which takes place in clockwise direction, the offset c^1 of the disc C will carry along with it the setting bolt D and together therewith the setting disc A until the bell crank lever 20 F will come to strike against the toe of the depressed key. The bell crank lever F is thereby rocked on its pivot a^1 and the setting bolt D shifted so as to cause it to release the offset c^1 of the driving disc C and 25 to engage one of the notches g^1 of the locking plate G by its free end. The setting bolt D and, consequently, the setting disc A too, are held in this position by the rim c^4 of the driving disc C gliding along the toe 30 of the setting bolt D during the continued oscillation of the driving disc.

The rotation of the setting disc A will cause the pinion J, which engages its toothed rim a^3 , and the adding mechanism connected therewith to be adjusted and the planet-pinion H as well as the intermediate pinion K to be rotated. However, the double segment L and the toothed wheel N are not yet moved because of the larger mass 40 and friction of the display, type and intermediate wheels, but the intermediate wheel K will roll in clockwise direction along the toothed rim L' which is still stationary, the planet-pinion H likewise rolling at the revolving toothed rim a^3 but in the opposite direction so that the planet-pinion carrier E will be rocked in clockwise direction at a 45 lower speed than the setting disc A.

In the position of rest of the machine the 50 planet-pinion carrier E is in a position, which depends on the value of the key depressed at the previous operation of the cash register. The distance between the recess e^2 and the stop M is the larger the higher the 55 value of that depressed key. In the case no key was depressed the recess e^2 touches the stop M.

It will be assumed that now a higher key 60 (key 6) than in the previous cash register operation (key 3) is depressed. During the rotation of the setting disc A first of all the carrier E is taken along up to the stop M, whereby the intermediate pinion K rolls over the toothed rim L' and the planet pinion H rolls in a different manner over the

toothed rim a^3 . During this part of movement the double segment L in consequence of larger mass and friction of the parts connected with it remains in its position. At the moment the recess e^2 touches the stop M 70 the setting disc A possesses a position which corresponds to the key depressed at the previous operation of the cash register (position 3). During the further movement up to the stoppage (position 6) the carrier E 75 rests in its zero position arrested by the stop M. The gearing a^3 , H, H', K, L', L, N acts like a common wheel gearing supplied with fixed shafts and translates the remainder movement of the setting disc A (3 units) 80 on the wheel N adjusting the display and type wheels in a clockwise direction. Thus the display and type wheels are moved directly from the old (position 3) into the new position (position 6). 85

When depressing however, the same key (key 3) as in the previous registration the carrier E will reach its stop M at the moment the toothed rim a^3 is coming to rest, so that the toothed wheel N retains its position. 90

When depressing a key (key 7) lying lower than that operated in the previous operation of the cash register (key 3), the carrier E by the motion of the disc A is not 95 brought up to the stop M but only to a position at which the distance between the recess e^2 and the stop M corresponds to a number of units depending on the difference between the said two keys (2 units). After the 100 toothed rim a^3 has come to rest in pin c^2 of the disc C will push the carrier E forward and takes it along up to the zero position, that is to say, up to the stop M. As in this case, however, contrary to the former case, 105 the toothed rim a^3 is stationary and the carrier E is being oscillated the planet-pinions H and H' will now rotate in a direction opposite to that before and the toothed wheel N will now be adjusted in counter clockwise 110 direction from the old (position 3) into the new position (position 1).

As soon as the reversal of the display and type wheels has been terminated, the toothed wheel N will be held in its new position by the locking bar O. In the return oscillation of the driving disc C its pin c^3 will engage the recess a^2 of the setting disc A and move the same back into its initial position, after the setting bolt D has been released from the rim c^4 of the driving disc C. The return rotation of the toothed rim a^3 caused thereby will likewise be imparted to the planet-pinion carrier E, so that the planet-pinion H will revolve at the toothed rim a^3 in clockwise direction until the carrier will stop, till the next operation of the cash register, at a distance from the stop M corresponding to the value of the key depressed last, since the degree of return oscil- 120 125 130

lation of the setting disc A depends upon this value.

The described arrangement offers the advantage that the new setting of the display and type wheels takes place at the beginning of the operation of the machine so that relatively much time remains for the printing operation. It would, however, not alter the spirit of the invention if the arrangement would be made so as to cause the setting discs to be returned to their zero-position at the beginning of the operation of the machine.

Claims:

15. 1. A device for setting the display and type wheels of cash registers, comprising setting discs, members rockable to and fro for driving the setting discs and means for rotating the display and type wheels directly from the old into the new position, a swingingly mounted carrier for a planet-pinion, means for positively connecting the said planet-pinion with the display and type wheels as well as with the respective setting disc, and a fixed stop for limiting the swinging movement of the planet-pinion carrier in one direction and determining the zero position into which the carrier is adapted to

be moved in the setting oscillation of the driving member of the setting disc. 30

2. A device for setting the display and type wheels of cash registers, comprising setting discs, members rockable to and fro for driving the setting discs and means for rotating the display and type wheels directly from the old into the new position, a swingingly mounted carrier for a planet-pinion, means for positively connecting the said planet-pinion with the display and type wheels as well as with the respective setting disc, a fixed stop for limiting the swinging movement of the planet-pinion carrier in one direction and determining the zero position into which the carrier is adapted to be moved in the setting oscillation of the driving member of the setting disc, and a driver on the said driving member, said driver being adapted to engage the planet-pinion carrier in each setting oscillation of the driving member so as to secure the return of the planet-pinion carrier to its zero position in each setting operation. 35 40 45 50

The foregoing specification signed at Essen, Germany, this 28th day of July, 1922.

WERNER KOLBE.
